UNITED STATES PATENT OFFICE.

WILLIAM HARPER, JR., OF NEW BLOOMFIELD, PENNSYLVANIA, ASSIGNOR, BY MESNE ASSIGNMENTS, OF THREE-TENTHS TO HARPER ENGINEERING COMPANY, A CORPORATION OF NEW YORK, AND SEVEN-TENTHS TO THOMAS A. NEVINS, OF EAST ORANGE, NEW JERSEY.

INTERNAL-COMBUSTION ENGINE.

1,189,564.

Specification of Letters Patent.

Patented July 4, 1916.

Application filed June 10, 1907, Serial No. 379,147. Renewed October 30, 1912. Serial No. 728,726.

To all whom it may concern:

Be it known that I, WILLIAM HARPER, JR., a citizen of the United States of America, and a resident of New Bloomfield, Perry county, Pennsylvania, have invented certain new and useful Improvements in Internal-Combustion Engines, of which the following is a specification.

This invention relates particularly to the means for charging oil to an internal combustion engine and insuring the intimate mixture of the oil with air in the power chamber.

One object of the invention is to utilize, particularly in a multiple engine arrangement in which the engines are in spaced phase, a portion of the compressed charge of each engine in the operation of the atomizer of a different engine, whereby the atomizer in each engine is intermittently operated and at the proper moment.

A further object of the invention is to construct an adjustable atomizer nozzle which passes through the wall of the engine, the adjustment of the nozzle within the engine being effected by rotating the nozzle outside the engine.

In the accompanying three sheets of drawings, which form a part of this application, Figure 1 is an elevation of a battery of three two-cycle engines embodying my invention, the crank cases for the engines being in section. Fig. 2 is a longitudinal section through one of the engines with the compression stroke at two-thirds point. Fig. 3 is a longitudinal section through one of the engines showing the piston at the lowest point of the stroke. Fig. 4 is a section through the wall of an engine cylinder drawn to larger scale and showing the atomizer nozzle at widest open adjustment for air admission. Fig. 5 is a similar section showing the atomizer nozzle adjusted for restricted air flow. Fig. 6 is a plan view of the deflector plate. Fig. 7 is a transverse section through the power chamber of an engine on the line VII—VII of Fig. 3. Fig. 8 is a transverse section through the cylinder forming the main and the auxiliary com-

pression chambers of an engine on the line VIII—VIII of Fig. 2.

The drawings show a battery of three engines A' A² A³ operating in spaced relation so that they follow each other in power impulse at each third of a revolution.

55

Each engine comprises a cylinder a closed at the top and underneath a cylinder b of larger internal diameter and tandem with the first cylinder, there being a step c at the point of juncture of the two cylinders owing to their difference in diameter. Both cylinders are traversed by a hollow piston consisting of a head d fitting the smaller cylinder, and a head e fitting the larger cylinder. A connecting rod f connects the piston with the crank of the crank-shaft g of the engine. The larger cylinder is closed, in effect, at the bottom by the crank-case h. Three chambers are formed by the cylinders and piston: above the piston and in the smaller cylinder is formed the power chamber; below the piston and in the larger cylinder and in the crank-case is formed the main compression chamber, which also takes in the crank-case space and the interior of the piston; and between the wall of the piston intermediate of its two heads and the wall of the larger cylinder is formed an annular compression chamber.

Air for the engine is drawn into the main compression chamber through rotary valves i i carried by the crank-shaft which open and close ports j j in the crank-case. Clearance spaces k k are formed at the upper end of the larger cylinder and are in unobstructed communication with the upper end of the annular compression chamber, and these spaces are in effect a clearance space for the annular compression chamber, which is afforded without lengthening the chamber for the purpose. Air is drawn into the annular compression chamber through a check valve l set in one of the clearance spaces. Ports m m at the lower edge of the rim of the piston come into communication with the clearance spaces when the piston nears the upper point of its stroke and permit the escape of the compressed air to the interior of the

- piston and the compression chamber of the larger cylinder. Deflectors n in the lower edge of the rim of the piston serve to direct the inrushing air upwardly to the top of the 5 chamber in the piston. Three ports o open into the power chamber of the smaller cylinder when the piston is at the lowest point of its stroke, they being at other times covered by the piston. A passageway p 10 leads from the main compression chamber through the crank-case to these ports. An oil nozzle q is located opposite the middle of the three ports and sprays oil into the draft of the incoming charge to the power chamber. The oil is delivered to the nozzle 15 through a hollow feed shaft r which is revolved in synchronism with the crank-shaft, and is supplied with oil through a pipe s . The oil nozzle lies within a nozzle t to 20 which air is supplied under pressure at the proper moment when the ports are uncovered by the piston, and the oil is thereby atomized and directed into the power chamber.
- 25 To secure the air for atomizing under pressure at the proper moment, advantage is taken of the usual multiple arrangement of engines of this type, operating in spaced relation. A battery of three engines following each other at intervals of one hundred 30 and twenty degrees of crank revolution is especially suited, since a charge of air under high compression may be drawn from the annular compression chamber at the two-thirds point of an up-stroke, as shown in 35 Fig. 2, and conducted through a tube u to the atomizing nozzle of another engine, which at the same moment is at the lowest point of its stroke as shown in Fig. 3. In 40 this way the annular compression chambers of the engines A' A^2 A^3 are connected respectively to the atomizing nozzles of the engines A^2 A^3 and A' . The air emerges 45 from the nozzle through a circular aperture surrounding the mouth of the oil nozzle. The exterior of the oil nozzle is tapered and means are provided for adjusting the mouth of the air nozzle along this taper and thereby adjusting the width of the circular aperture. For this purpose the air 50 nozzle is interiorly threaded at v and screws onto an enlarged part of the shank of the oil nozzle. This nozzle is exteriorly threaded at w and screws into the wall of the engine. 55 The threads are of the same pitch so that on rotating the air nozzle it screws into the engine as its screws off from the oil-nozzle shank, thereby effecting the adjustment without changing the position of the oil nozzle 60 or disturbing the alinement of the hollow shaft. The atomized oil with the air from the passageway leading from the main compression chamber and through the middle port, forms a rich mixture which is blown
- against the middle upwardly curved section x of a deflector plate mounted on the piston head. This plate is hot and vaporizes any oil particles which may fail of proper comminution by the atomizer. The deflector plate has laterally curved sections x' at either side of the middle section and opposite the two ports on either side of the port containing the nozzle. These laterally curved sections deflect the air from the side ports into the rich mixture from the central port and the three streams are thereby combined and directed upwardly into the power chamber. Exhaust ports y are located in the walls of the power chamber where they will be uncovered at the proper time by the piston.
- The engine is water-jacketed, but to prevent undue cooling by the water, round wire z is coiled about the cylinder. The small spaces between the wire and cylinder become filled with steam and heat is therefore removed by the water indirectly from the cylinder wall, and only as fast as it can be conducted from the cylinder wall through its point of contact with the wire and by the steam which forms and becomes trapped in the triangular spaces between the coils and the wall of the cylinder.
- In operation each engine draws in charges of air or mixture, as may be desired, to the main compression chamber and the annular compression chamber, combines these charges and transfers them to the power chamber, as set forth in my application for Letters Patent of the United States Serial No. 347,430, filed December 12, 1906, and in addition, a portion of the compressed charge, usually of air, in the annular compression chamber of each engine is taken to the atomizer of another engine as above set forth.
- The atomizer brings the charge up to the desired degree of enrichment, and the charges which are drawn into the compression chambers are preferably kept lean so that they will not be prematurely fired.
- What I claim as new and desire to secure by Letters Patent of the United States is:
1. The combination of a plurality of internal combustion engines operating in spaced phase, each engine being provided with an atomizer for supplying a charge thereto and an air compression means, and connections between the atomizer of each engine and the air compression means of a different engine, substantially as described.
  2. The combination of three internal combustion engines operating in spaced phase, each engine being provided with an atomizer for supplying a charge thereto and an air compression means, and connections between the atomizer of each engine and the air compression means of a different engine, substantially as described.

3. The combination of three internal combustion engines operating in spaced phase, each engine comprising tandem communicating cylinders of different diameters, a piston fitting both cylinders and forming a power chamber in the smaller cylinder and an annular air compression chamber between the walls of the piston and the walls of the larger cylinder, and connections between the

atomizer of each engine and the compression chamber of a different engine, substantially as described.

Signed by me at New York, N. Y., this seventh day of June, 1907.

WILLIAM HARPER, JR.
